FABRIC TENSIONING MECHANISM

Eugene St. Pierre, Pawtucket, R. I., assignor to Hemphill Company, Pawtucket, R. I., a corporation of Massachusetts

Application February 3, 1954, Serial No. 407,837

6 Claims. (Cl. 66—150)

This invention relates to knitting machines. It is particularly concerned with fabric tensioning or takeup devices for use in such machines, especially those which knit rib top stockings.

When rib top stockings are knit in string-work, i. e., with the top of one attached to the toe of another, it is necessary to exert tension on the fabric of the toe pocket of the last knit stocking, while the rib top of its successor is knit in, in order to compensate for the unequal pull of the fabric takeup which pulls on the instep half of the stocking directly from the needles but is prevented from applying the same tension to the other half of the fabric, because of the loose toe pocket lying between it and the needles. This tension is also necessary to aid the rib needles, either dial or upper cylinder, in casting off their stitches, and to prevent the rib loops in the wales above the loose toe pocket from catching in needle hooks or latches. It has been common practice in the knitting art to use some form of toe pocket pusher to provide this required tension.

The object of the present invention is to provide a fabric tensioning device or toe pocket pusher which will be more dependable in operation than those of the prior art. This is accomplished by providing the toe pocket pusher with fabric engaging elements and inserting a fabric guiding member within the needle cylinder which is slotted to accommodate the fabric engaging elements. A safety lock is included to prevent damage to the mechanism if withdrawal is attempted when the pusher is extended down inside the needle cylinder.

A preferred embodiment of the invention as applied to a circular, independent needle, knitting machine of the dial and cylinder type will be explained with reference to the accompanying drawings in which:

Figure 1 is a sectional elevation of the mechanism;

Figure 2 is an interior view of part of the fabric guiding cylinder;

Figure 3 is a top view of a partial section along the lines 3—3 of Figure 1;

Figure 4 is a top view of the pusher rod guide.

Figure 5 is a perspective of part of the pusher rod operating mechanism;

Figure 6 is a perspective of a continuation of the same mechanism; and

Figure 7 is a side view of the safety lock mechanism.

The mechanism of Fig. 1 represents the invention as employed in a conventional dial rib machine of the Banner type. A needle bearing cylinder 1 is bolted to a rotatable ring gear 2 in the circular base (not shown) of the machine and has a dial 3 rotatable with a shaft 4 which turns in a bearing (not shown) on the dial cam plate 5.

The shaft 4 is hollow to accommodate a pusher rod 6. This permits the rod 6 to move a toe pocket pusher 7 which is fixed to the bottom end of the rod up and down within the needle cylinder in a manner, and by a mechanism, later to be described.

The pusher 7 has a number of fabric engaging elements 8 secured to it. In the embodiment shown, these

2

elements consist of needle-like members which are adjustably secured to the main body of the pusher by set screws 9. These elements 8 engage the loose fabric of the toe pocket and, due to the weight of the pusher, exert a direct tension on the loops as they are formed on the needles.

To ensure that the members 8 will engage the fabric, a fabric guiding member 10 is provided. In the present instance, this fabric guide consists of a cylindrical sleeve which is mounted concentrically within the needle bearing cylinder 1. A connecting ring 11 fastened to the fabric guide 10 is secured to the needle cylinder 1 and the ring gear 2 by screws 12.

The fabric guiding sleeve 10 is provided with a number of slots 14 (Fig. 2), one for each of the fabric engaging elements 8. The purpose of these slots is to assure that the points of the elements 8 will not be bent or damaged by impact against the sleeve 10 and consequently become less effective or damage the fabric.

The slots 15 (Fig. 3) in the underlip 13 of the fabric guiding sleeve 10, through which it is fastened to the connecting ring 11, are elongated to permit a certain amount of adjustment of the sleeve 10 to align the slots 14 with the fabric engaging elements 8.

The pusher rod 6 is flat and passes through a rectangular opening 16 in the rod guiding member 17 which is fastened to the top of the dial shaft 4. This assures that the pusher 7 will rotate with the dial 3 which, in turn, is rotating with the needle cylinder. Consequently, no relative motion can take place between it and the fabric pusher 7. This assures that the fabric engaging elements 8 of the pusher 7 will always engage the toe pocket and not some other part of the stocking.

As referred to above, if the fabric pusher 7 is allowed to fall freely at the proper time, its needle-like elements 8 will engage the fabric of the toe pocket and the weight of the pusher 7 will take up the slack in the pocket and exert a steady uniform tension on the corresponding cylinder and dial loops as they are formed on the knitting needles. As more and more courses of rib fabric are knit, the pusher element 7 falls deeper into the needle cylinder. After the rib top is completed or the fabric has become long enough so that the toe pocket reaches the regular takeup (not shown), the tensioning action of the fabric pusher is no longer required and it is returned to its initial position at the top of the cylinder, immediately below the dial, as shown in dotted lines in Figure 1.

The mechanism for raising the pusher 7 to this position is shown in Figures 5 and 6. It includes a cam 18 on a drum 19, a rocker 20 which is operated by the cam 18, and a series of associated rods and levers.

The top of the pusher rod 6 is held by a bracket 21 which is carried by a lever 22 and its extensions 23. The lever 22 is supported on the carrier ring 24 by a combination of brackets 25 and 26. It is pivoted on bracket 26 at 27 by the action of a rod 28. Rod 28, in turn, is reciprocated longitudinally by a centrally pivoted lever 29 which is operated by the rocker 20 through a connecting rod 30. When the nose of rocker 20 rides up onto a cam 18 on the drum 19, its tail exerts a downward thrust on the rod 30. This pivots the lever 29 so as to exert an upward thrust on the rod 28, thereby pivoting the lever 22 at 27 so as to raise its extensions 23 and thus raise the rod 6 and pull pusher 7 to the top of the needle cylinder.

The carrier ring 24 is hinged at 31 so that the dial and its associated mechanism can be swung back from the top of the cylinder to permit access thereto or independent knitting thereon. However, if the dial were 70 swung back while the rod 6 is extended down inside the cylinder 1, the pusher element 7 would not clear the fabric guiding element 10 within the cylinder and a bent

rod 6, along with damage to the fabric pusher 7, or the fabric guide 10, would result. To protect against this, the safety lock shown in Figures 5 and 7 is provided.

This safety lock comprises a stud 32 in the tail of the carrier ring 24 behind the hinge 31. A latch 33 pivoted on a bracket 34 which is secured to the frame of the machine is held by a spring 35 so as to be normally in engagement with the stud 32 and thereby prevent the carrier ring 24 from being swung backwards from the top of the cylinder 1. When, however, the nose of rocker 20 is riding on a cam 18 and rod 30 is consequently pulled downwards to raise the rod 6 and pusher element 7 as described above, a pin 36 at the junction of rod 30 and lever 29 bears against the latch 33 and disengages it from the stud 32. This permits the carrier ring 24 to be rocked backward away from the cylinder 1 when, and only when, the rod 6 is clear of the needle cylinder 1 and the pusher element 7 is raised up close to the dial 3.

The invention has been described with reference to rib knitting on a dial and cylinder machine, but it is equally applicable to two-cylinder machines and other fabric take-up and tensioning problems.

I claim:

1. In or for a circular, independent needle, knitting machine a needle bearing cylinder, a needle bearing dial having a passage therethrough, a dial supporting member capable of being moved between a position where said dial is proximate said cylinder and a position where it is more remote from said cylinder, a fabric guiding member, a fabric pushing member movable in relation to said fabric guiding member, said fabric pushing member being mounted on a pusher rod which passes through said passage in said dial so as to permit movement of said pushing element between a high and a low position within said cylinder, and a locking device acting upon said dial supporting member to prevent it from being moved to said remote position when said pushing element is in said low position.

2. The invention according to claim 1 and wherein means comprising a series of levers and a cam operated rocker is connected to said pusher rod for moving said fabric pushing element.

3. The invention according to claim 2 wherein said locking device comprises a latch and stud, and said latch is operated by one of said pusher rod operating levers.

4. The invention according to claim 1 wherein said fabric pushing member has fabric engaging elements, and said fabric guiding member comprises a cylindrical sleeve concentric with said needle bearing cylinder and having depressions to accommodate said fabric engaging elements.

5. In or for a circular, independent needle, knitting machine a rotatable needle bearing cylinder, a fabric guiding member rotatable with said cylinder, a rotatable fabric pushing member, a plurality of openings in and extending longitudinally of said fabric guiding member, a plurality of fabric engaging elements carried by said pushing member, means for aligning said elements with said openings, means for moving said pushing member longitudinally of said guiding member while both of said members are rotating, and means for preventing relative motion between said guiding member and said pushing member.

6. In a circular, independent needle, knitting machine, a rotatable needle bearing cylinder, a hollow shaft rotatable with said cylinder, a dial fixed to the lower end of said shaft, a closure for the upper end of said shaft having a non-circular opening communicating with the interior of said shaft, a rod having a longitudinally sliding fit within said opening and extending through said shaft, a fabric pushing member secured to said rod, fabric engaging elements carried by said pushing member, a fabric guiding member within and rotatable with said cylinder and having longitudinal openings, and means for aligning said fabric engaging elements with said openings.
